DESIGN FOR A TEXTILE FABRIC

Edward G. Meyers, Maplewood, N. J., assignor to Pacific Mills, Lawrence, Mass., a corporation of Massachusetts

Application January 10, 1939, Serial No. 82,264

Term of patent 3½ years

To all whom it may concern:

Be it known that I, Edward G. Meyers, a citizen of the United States residing at 9 East Cedar Lane, Maplewood, New Jersey, have invented a new, original, and ornamental Design for Textile Fabrics, of which the following is a specification, reference being had to the accompanying drawing, forming a part thereof.

The figure is a plan view of a textile fabric showing my new design.

My design consists of a series of groups of darts on a plain field, three darts of each group being interlaced and a fourth dart being slightly separated from the group, in some of the groups.

I claim:

The ornamental design for a textile fabric, as shown and described.

EDWARD G. MEYERS.
